US0D1038870S

(12) **United States Design Patent** (10) Patent No.: **US D1,038,870 S**
(45) Date of Patent: ** Aug. 13, 2024

(54) **CHARGING STATION**

(71) Applicant: **Parabit Systems, Inc.**, Roosevelt, NY (US)

(72) Inventors: **Robert J. Leiponis**, Glen Cove, NY (US); **Wilson M. Lee**, Valley Stream, NY (US)

(73) Assignee: **Parabit Systems, Inc.**, Roosevelt, NY (US)

(**) Term: **15 Years**

(21) Appl. No.: **29/837,033**

(22) Filed: **May 1, 2022**

(51) LOC (14) Cl. **13-02**

(52) U.S. Cl.

USPC **D13/107**

(58) **Field of Classification Search**

USPC D13/103, 107, 108, 116, 118, 120, 133, D13/154, 184, 199; D6/641

CLAIM

The ornamental design for a charging station, as shown and described.

DESCRIPTION

FIG. 1 is a front, top, right perspective view of a charging station according to a first embodiment of our new design;

FIG. 2 is rear, top, left perspective view of the charging station shown in FIG. 1;
FIG. 3 is a front elevational view of the charging station shown in FIG. 1;
FIG. 4 is a rear elevational view of the charging station shown in FIG. 1;
FIG. 5 is a right side elevational view of the charging station shown in FIG. 1;
FIG. 6 is a left side elevational view of the charging station shown in FIG. 1;
FIG. 7 is a top plan view of the charging station shown in FIG. 1;
FIG. 8 is a bottom plan view of the charging station shown in FIG. 1;
FIG. 9 is a front, top, right perspective view of a charging station according to a second embodiment of our new design;
FIG. 10 is rear, top, left perspective view of the charging station shown in FIG. 9;

FIG. 11 is a front elevational view of the charging station shown in FIG. 9;
FIG. 12 is a rear elevational view of the charging station shown in FIG. 9;
FIG. 13 is a right side elevational view of the charging station shown in FIG. 9;
FIG. 14 is a left side elevational view of the charging station shown in FIG. 9;
FIG. 15 is a top plan view of the charging station shown in FIG. 9; and,
FIG. 16 is a bottom plan view of the charging station shown in FIG. 9.
The dash-dash broken lines depict portions of the charging station that form no part of the claimed design. The dot-dash broken lines depict a symbolic break in the article. The portions between the break lines form no part of the claimed design.
